UNITED STATES PATENT OFFICE

135,921

DESIGN FOR A RAZOR BLADE

Joseph Rene Ayotte, Chicago, Ill.

Application June 22, 1942, Serial No. 107,292

Term of patent 14 years

To all whom it may concern:

Be it known that I, Joseph Rene Ayotte, a citizen of the United States, residing at Chicago, in the county of Cook and State of Illinois, have invented a new, original, and ornamental Design for a Razor Blade, of which the following is a specification, reference being had to the accompanying drawing, forming part thereof.

In the drawing:

I claim:

The ornamental design for a razor blade, as shown.

JOSEPH RENE AYOTTE.
